FUSE LEAD CONSTRUCTION FOR ELECTRIC
LAMPS

Waldemar E. Anderson, Montclair, N. J., assignor
to Westinghouse Electric & Manufacturing
Company, East Pittsburgh, Pa., a corporation
of Pennsylvania

Application May 13, 1938, Serial No. 207,704

18 Claims. (Cl. 176—38)

This invention relates to electric lamps and more particularly to the construction of the fuse lead in high wattage lamps generally designated as bipost lamps.

During recent years it has become the practice to use fuses in certain classes of gas-filled lamps, for protection against destructive arcs upon failure of the lamp filament. The designs commonly used previously either incorporate the fuse element in one of the leads exterior of the lamp bulb; for example, in the stem-tube between the press and the base, or internal as a part of the inner lead between the press and the filament. In both designs, however, the fuse has always been of the series type where the lead is assembled by butt-welding the different parts together one after the other.

In bipost lamps, however, only the internal type of fuse is practicably applicable and since the lead wires must carry the entire mechanical load of the internal structure of the lamp, as well as the current, the series type of fuse introduces a weak link in the supporting structure which necessitates the use of expensive bracing parts to permit shipping the lamp and to withstand ordinary handling by the user. Likewise, the secondary arc produced by the operation of the fuse, when the lamp fails hot, tends to maintain itself between the ends of the adjacent larger parts of the lead wires, producing a comparatively large amount of hot metal and fuse cover material which scatters onto the bulb, resulting in consequent danger of breakage or explosion.

To overcome such objections, as well as avoid the necessity for expensive butt-welding equipment, I have designed and demonstrated in lamps, a fuse lead construction which not only eliminates hazards from secondary arcs produced by the operation of the fuse itself, and provides a rigid structure to withstand shipping and handling; but is also much less expensive to manufacture.

It is, therefore, a principal object of my invention to provide a gas-filled lamp, particularly of the bipost construction, comprising a rigid mount including a fuse, in order to avoid destructive arcs upon failure of the lamp, said mount being formed so as to avoid being weakened by the fuse lead feature.

Another object of my invention is the provision of a high-wattage lamp of the bipost type comprising a rigid mount, associated with one of the leads of which is a fuse.

A further object of my invention is the provision of a fused bipost lamp, which avoids butt-

weld fuses and substitutes what might be termed a shunt fuse arrangement.

A still further object of my invention is the formation of a construction for lamps in which a fuse is so enclosed that arcing, upon failure of the lamp and the operation of the fuse, is minimized.

Other objects and advantages of the invention relating to the particular arrangement and construction of the various parts will become apparent as the description proceeds.

In the drawings:

Fig. 1 is a side elevational view of an incandescent electric lamp of the bipost type embodying my invention.

Fig. 2 is an enlarged detail view of the fuse portion of the lamp of Fig. 1, partly on line II—II of Fig. 3, in the direction of the arrows.

Fig. 3 is an enlarged horizontal sectional view on the line III—III of Fig. 2, in the direction of the arrows.

Fig. 4 is an elevational view of the base and leads of the lamp of Fig. 1, prior to insertion of the fuse.

Fig. 5 is a partial elevational and partial vertical sectional view, as in Fig. 2, of a fuse for a lamp such as shown in Fig. 1, but illustrating a modification.

Fig. 6 is a view corresponding to Fig. 5, but showing another embodiment of my invention.

Fig. 7 is a fragmentary view of a portion of a bipost lamp corresponding generally to Fig. 1, but showing another embodiment of my invention.

Fig. 8 is an enlarged detailed view of the fuse lead, on the line VIII—VIII of Fig. 7, in the direction of the arrows.

Fig. 9 is an enlarged horizontal sectional view of said lead on the line IX—IX of Fig. 7, in the direction of the arrows.

Fig. 10 is an elevational view of a mount for another embodiment of my invention.

Fig. 11 is a fragmentary elevational view on the line XI—XI of Fig. 10, in the direction of the arrows.

Fig. 12 is an enlarged horizontal sectional view on the line XII—XII of Fig. 10, in the direction of the arrows.

Referring to the drawings in detail, like parts being designated by like reference characters, and first considering the embodiment of my invention illustrated in Figs. 1 to 4, inclusive, there is shown a high-wattage lamp 14, of the medium bipost type, comprising an envelope 15 provided with a base 16, through which extend leading-in 15

conductors 17 and 18 from terminal posts 19 and 21.

The leading-in conductors 17 and 18 may be formed hollow to receive the conductors or support leads 22 and 23, the lower ends of which may be secured to said conductors 17 and 18 in any desired manner as by crimping, as indicated at 24 and 25. The free or upper ends of the conductors 22 and 23 are, in the present embodiment, connected by wires 26 and 27, the outer ends of which are spot-welded thereto, and the inner ends embedded in a glass or other insulating portion 28. Intermediate portions of the conductors 22 and 23 are likewise connected by wires 29 and 30, the outer ends of which are embedded in a glass or other insulating portion 31.

The filament 32, illustrated as of the coiled variety, is shown mounted between the conductors 22 and 23 and the insulators 28 and 31, the end sections 20 of said filament being fitted over stiffening wires 40, and filament and wires welded or otherwise secured to the conductors 22 and 23, and the intermediate portions draped over hooks 33, 34, and 35, extending from the insulator 28 and hooks 36 and 37, extending from the corresponding insulator 31.

The insulators 28 and 31 also desirably carry wires or spuds which serve to support screens or other means for collecting material vaporized from the filament, thereby minimizing the blackening of the bulb. For this purpose, the insulator 28 has spuds or support wires 38 and 39 which extend laterally therefrom and to which the vaporized metal collecting screen 41 is secured, as by means of spot-welding. The screen 41 may be inverted V-shaped, as viewed from the side (not shown), and straddle the insulator 28, see the corresponding screen shown in Fig. 11. The elements or arms of the screen 41 are secured to the corresponding spuds extending from opposite sides of the insulator 28.

In the same way, a vaporized metal collecting screen 42 is desirably supported from the insulator 31 by spuds or wires 43 and 44 extending from the sides thereof and to which the screen is desirably spot-welded. The screen 42 is desirably V-shaped, like the corresponding screen illustrated in Fig. 11 and straddles the insulator 31, like the screen 41 thereabove.

When the envelope 15 has been filled with an inert gas and sealed, the lamp, as just described, is one of the high-wattage type, suitable for projection or general lighting purposes. On account of carrying the necessary high current, failure of the filament is apt to result in a destructive arc between the adjacent ends of said filament. In order to avoid such an arcing, I provide, in the present embodiment, a fuse 45 for the conductor 23. This fuse may be inserted by cutting the conductor 23 at the point 46, as shown in Fig. 4, as by means of shears 47, and then fitting an insulating lead-bracing tube 48 over the stub 49 of the conductor 23, as shown most clearly in Fig. 2.

After applying a glass or refractory bead 51 in the tube 48 above the free end of the stub 49, I thereafter insert the portion 52 of the conductor 23, which was cut off in the operation described in connection with Fig. 4, thereby rigidly uniting the adjacent ends of the portions 49 and 52, while at the same time insulating them against the flow of current therebetween. The tube 48 is desirably formed of a rigid refractory "Alsimag," which is a kind of porcelain or re-

fractory like lava, being mentioned as an example, but, if desired, a glass tube may instead be satisfactorily used.

The fuse 45 of the present embodiment is formed as a wire of nickel, or other suitable fuse material, of sufficient cross section to carry the normal current without overheating, but which will fail by fusion upon the passage of excessive current which might flow upon the formation of an arc between the broken ends of the filament 10 32. The fuse 45 has most of its length enclosed in a tube 53, which may be of material corresponding with that of the tube 48, that is of Alsimag, glass, or the like, as desired. The free ends of the wire 45 are desirably wound around 15 the lead sections 49 and 52 and spot-welded thereto, as indicated at 54 and 55, thereby tightly holding said lead portions together and preventing their removal from the tube 48.

By positioning the fuse 45 parallel to the adjacent ends of the supporting lead sections 49 and 52, I provide a structure which is sufficiently rigid to withstand shipping and handling and is also much less expensive to manufacture. The close fitting refractory or glass tube 48 provides rigidity for the lead 23, practically equivalent to that before cutting, and the fuse 45, of suitable size and material, ties the two parts of the main lead together, producing a rigid unit. With a close fitting refractory, tube 53, over the fuse, the 30 action thereof is of the explosion type; that is, melting occurs inside, rather than outside, of the tube 53, due to said tube acting as a heat insulator, whereby upon melting, the metal vapors formed forcibly blow out the fuse sections at 35 the ends of the cover tube, thereby quenching the arc formed by blowing it apart. Lamps manufactured with this type of fuse lead construction have shown it to be effective.

Referring now to the embodiment of my invention illustrated in Fig. 5, the fuse lead 23^a is there shown interrupted and provided with a portion 45^a reduced in section to correspond with that of the fuse 45 of the preceding embodiment. This section is desirably constructed of a piece 45 of nickel, or other suitable fuse material, of proper dimensions to provide the desired fuse characteristics, and has its ends secured to the adjacent ends of the heavy lead portions 49^a and 52^a, as by welding, indicated at 54^a and 55^a.

The composite lead 23^a then has applied thereover a refractory, glass, or other insulating tube 48^a, desirably closely fitting the heavy lead portions 49^a and 52^a, and secured in place in any desired manner as by means of metal spuds 56 and 57, welded or otherwise secured to the lead sections 49^a and 52^a adjacent the ends of the tube 48^a. In the present embodiment, the lead-bracing tube 48^a is shown provided with a hole 58 in its side, pointing away from the other lead (not shown), so that the air will be efficiently exhausted therefrom during manufacture of the lamp, and any vapors formed during melting of the fuse 45^a are discharged away from said other lead.

Fig. 6 illustrates an embodiment of my invention corresponding with the fuse arrangement of Fig. 5, with modified features. Although the tube 48^b preferably closely fits the lead sections 49^b and 52^b, it need not fit closely, as the construction is here rigidified by coils of wire 59 and 60 which closely surround the ends of the lead-bracing tube 48^b and have their outermost ends coiled around the lead sections 49^b and 52^b and welded or otherwise secured thereto, as indi- 75

cated at 61 and 62. If the tube 48^b loosely fits the sections 49^b and 52^b, the aperture 58^b may be omitted as the space around loose-fitting sections serves the same purpose. It will therefore be seen that this construction provides additional rigidity by securing the ends of the tube 48^b to the main lead sections 49^b and 52^b by supplemental wire portions, in addition to the fitting of the lead sections in the tube itself.

10 Referring now to the embodiment of my invention illustrated in Figs. 7, 8, and 9, there is shown a fragmentary portion of a medium bipost lamp 14^c comprising an envelope 15^c provided with a base 16^c through which extend leading-15 in conductors 17^c and 18^c, from terminal posts 19^c and 21^c.

Extending from the conductors 17^c and 18^c are support leads 22^c and 23^c connected by wires 29^c and 30^c, the outer ends of which are spot-welded 20 thereto and the inner ends embedded in a glass or other insulating portion 31^c. Although only the lower bracing device 29^c, 30^c, 31^c is shown, it will be understood that the upper ends of the support leads are desirably connected by a bracing 25 device similar to that shown in Fig. 1 and designated by the reference characters 26, 27, 28. However, the filament may instead be supported as in the embodiment of Figs. 10, 11, and 12. Between the leads 22^c, 23^c, and the bracing devices, or above or beyond the bracing device, is mounted an incandescent filament desirably corresponding with that designated by the reference character 32 in Fig. 1. As in Fig. 1, screens, or only one, as shown and designated by the reference character 42^c, may be employed for collecting vaporized filamentary material during 35 operation of the lamp.

In the present embodiment, the lead 23^c is formed in two sections: a lower section 49^c and 40 an upper section 52^c. The section 49^c is secured to a metal connector plate 63 as by welding, and the section 52^c is secured to a similar metal connecting plate 64, desirably in the same manner. These plates are separated by an insulating 45 plate of mica or other suitable material 65, and held in assembled relation, as illustrated, by bolts 66 and nuts 67 passing through associated insulating washers 68 and 69, and suitable apertures in the associated plates 63, 64, and 65, in 50 order to rigidly connect the parts 49^c and 52^c, forming the support lead 23^c, while insuring that said parts are insulated from one another.

As in the embodiment of Figs. 1 to 4, inclusive, I provide a bipass or parallel fuse device 71 55 which, in the present embodiment, consists of terminal wires 72 and 73 tightly fitting in the ends of an insulating bracing tube 48^c formed of refractory material or glass, like the tube 48 of the first embodiment. Between the enclosed end 60 portions of the terminal wires 72 and 73 which form in effect extensions of the lead sections 52^c and 49^c, extends a fuse wire 45^c, which may correspond with the fuse wire 45 of the first embodiment. The ends of the members 72 and 73 65 are desirably bent at right angles to the tube 48^c and respectively secured to the upper lead section 52^c and the lower lead section 49^c, as by spot-welding or in any desired manner, thereby further rigidifying the connection between the 70 lead sections 49^c and 52^c.

Referring now to the embodiment of my invention illustrated in Figs. 10, 11, and 12, there is disclosed a mount for a medium bipost lamp, said mount being provided with a base 16^d and 75 leading-in conductors 17^d and 18^d having ter-

minal posts 19^d and 20^d. Extending from the conductor 17^d, is a relatively thick or heavy support lead 22^d, to the upper end of which is secured an angular extension 74, as by spot-welding indicated at 75, and a short piece of wire or 5 spud 76 carrying a glass insulator 77.

Extending from the leading-in conductor 18^d is a relatively thin or light support lead 23^d formed as a lower section 49^d, and an upper section 52^d, said sections having their adjacent ends 10 tightly fitted in an insulating bracing tube 48^d, formed of glass or refractory material, and electrically connected by a fuse wire 45^d extending through said tube. In order to further brace the relatively light fused lead 23^d, the tube 48^d is 15 bound to the relatively heavy lead 22^d by straps or wires 78 and 79, so that the whole structure is rigidified.

The upper section 52^d of the lead 23^d is desirably angular and connected to the angular lead 20 extension 74 by wires 29^d and 30^d, the outer ends of which are spot-welded thereto and the inner ends embedded in the glass insulator 77. Said insulator carries supporting hooks 81, 82, 83, 84, and 85, over which a filament 32^d is draped, 25 the end sections 20^d of said filament being fitted over rigidifying wires 40^d, and filament and wires connected, as by welding, to the ends of the lead extension 74 and the upper lead section 52^d, as indicated at 86 and 87. As in the preceding 30 embodiments, an angular or V-shaped screen 42^d, for collecting vaporized filamentary material, may be carried by the insulator 77 through supporting spuds 43^d and 44^d.

In view of the foregoing disclosure, it will be 35 seen that I have devised a novel fuse lead construction, especially adapted for high-wattage lamps of the bipost type, and avoiding weakening the mounts of such lamps by the inclusion of a fuse in a supporting lead thereof, while at the 40 same time making it possible to manufacture such lamps economically and without serious manufacturing difficulties.

Although preferred embodiments of my invention have been disclosed, it will be understood 45 that other modifications may be made within the spirit and scope of the appended claims.

I claim:

1. An electric lamp comprising an envelope, a base for said envelope, a pair of support leads 50 extending from said base, a filament enclosed in said envelope and supported by said leads, insulating bracing means tightly fitting a portion of one of said leads, and a fuse associated with said bracing means. 55

2. An electric lamp comprising an envelope, a base for said envelope, a pair of support leads extending from said base, a filament enclosed in said envelope and supported by said leads, one of said leads being formed in two parts, insulating bracing means connecting said parts, and a fuse bypassing said bracing means. 60

3. An electric lamp comprising an envelope, a base for said envelope, a pair of support leads extending from said base, a filament enclosed in 65 said envelope and supported by said leads, one of said leads having an intermediate portion enclosed in an insulating tube and separated by an insulating member therein, and a fuse exterior of said tube, the ends of said fuse being connected 70 to said lead adjacent opposite ends of said tube.

4. An electric lamp comprising an envelope, a base, a pair of support leads extending from said base, a filament supported by said leads, one of 75 said leads being in two segments, and the adja-

- cent end portions of said segments fitted in an insulating tube while separated by an insulating member, and an insulated fuse device paralleling said tube and with its ends secured to said 5 lead segments beyond the tube.
5. An electric lamp comprising an envelope, a base, a pair of support leads extending from said base, a filament supported by said leads, one of said leads having a portion thereof reduced in 10 section to provide a fuse, and an insulating bracing tube tightly fitting said lead and enclosing said fuse.
6. An electric lamp comprising an envelope, a base, a pair of support leads extending from 15 said base, a filament supported by said leads, one of said leads being formed in two sections connected by a fuse, an insulating tube enclosing said fuse and receiving the adjacent ends of said sections, and a wire wound around each end portion of said tube and with its outer end secured to the lead section adjacent said tube.
7. An electric lamp comprising an envelope, a base, a pair of support leads extending from said base, a filament supported by said leads, one of 25 said leads being formed in two sections, the adjacent portions of said sections being secured to plates, separated by insulating means and connected together, so as to provide a rigid construction between said sections, while they are insulated from one another, and a fuse connecting 30 said insulated lead portions.
8. An electric lamp comprising an envelope, a base, a pair of support leads extending from said base, a filament supported by said leads, one of 35 said leads being relatively heavy and the other formed in two sections, the adjacent ends of which fit in an insulating tube and are connected by a fuse enclosed by said tube, and means binding said tube to the relatively heavy lead.
- 40 9. In a lamp, a fuse lead comprising a pair of conductors, the adjacent ends of which tightly fit an insulating bracing tube, and a fuse associated with said conductors to disrupt the passage of an abnormal flow of electric current 45 therethrough.
10. In a lamp, a fuse lead comprising a pair of conductors, the adjacent ends of which are tightly connected by an insulating bracing tube, and a fuse associated with said conductors to disrupt 50 the passage of an abnormal flow of electric current therethrough.
11. In a lamp, a fuse lead comprising a pair of conductors, the adjacent ends of which tightly fit an insulating tube, and are electrically insu-
lated by a plug disposed therebetween, and a fuse associated with said conductors to disrupt the passage of an abnormal flow of electric current therethrough.
12. In a lamp, a fuse lead for incandescent 5 electric lamps comprising a pair of conductors, the adjacent ends of which are insulated from each other and enclosed in an insulating tube, and a fuse exterior of said tube, the ends of said fuse being connected to said conductors adjacent 10 opposite ends of said tube to disrupt the passage of an abnormal flow of electric current there-
through.
13. In a lamp, a fuse lead for an incandescent 15 electric lamp comprising a pair of conductor sec-
tions, adjacent portions of which are fitted in an insulating tube, while separated by an insulating member, a fuse wire paralleling said tube with its ends secured to said lead segments beyond said 20 tube, and means enclosing said fuse.
14. In a lamp, a fuse lead comprising sup-
porting segments joined by a fuse, said fuse being enclosed in an insulating tube, the end portions of which closely receive said segments for rigidifying the connection. 25
15. In a lamp, a fuse lead comprising an insu-
lating tube, a fuse enclosed therein, supporting conductor sections, the adjacent ends of which fit said tube and are connected by said fuse, and wires closely wound around opposite ends of said 30 tube and with their outer ends secured to said sections.
16. In a lamp, a fuse lead comprising support-
ing conductor sections, the adjacent portions of 35 said sections being secured to plates, insulating means separating said plates, means connecting said plates together so as to provide a rigid union between said sections, while maintaining them insulated from one another, and a fuse connect-
ing portions of said sections and by-passing said 40 plates.
17. In a lamp, a fuse lead comprising a rela-
tively heavy supporting conductor, an insulating 45 tube bound thereto and enclosing a fuse, and lighter conductors with their adjacent ends fit-
ting in said tube and connected by said fuse.
18. An electric lamp comprising an envelope, a base for said envelope, a pair of support leads extending from said base, one of said leads being interrupted, a filament enclosed in said envelope 50 and supported by said leads, insulating bracing means tightly holding the interrupted portions of said leads, and a fuse joining said portions.

WALDEMAR E. ANDERSON.
